UNITED STATES PATENT OFFICE.

CHARLES E. BERTELS, OF WILKESBARRE, PENNSYLVANIA.

DESIGN FOR A LUNCH-PAIL BODY.

SPECIFICATION forming part of Design No. 34,166, dated March 5, 1901.

Application filed February 6, 1901. Serial No. 46,270. Term of patent 7 years.

To all whom it may concern:

Be it known that I, CHARLES E. BERTELS, a citizen of the United States, residing at Wilkesbarre, in the county of Luzerne and State of Pennsylvania, have invented and produced a new and original Design for a Lunch-Pail Body, of which the following is a specification.

The leading or material feature of the present design resides in an oblong lunch-pail body having vertical walls, the opposite side walls being flat and in parallel relation and the end walls connecting said side walls being continuously and convexedly curved to form circular arcs between the opposite ends of said flat side walls.

A minor feature of the design resides in providing upon the exterior walls of the lunch-pail body and intermediate its upper and lower edges a continuous ornamental band consisting of longitudinally-arranged spaced rows of beads and transverse lines of slight indentations between said rows.

In the drawings, Figure 1 is a perspective view of a receptacle-body of the new design. Fig. 2 is a side elevation of the same. Fig. 3 is a top plan view.

In said drawings the side walls are design-

nated by the numeral 10 and, as shown, are flat and arranged in parallel relation to each other. The opposite ends of said side walls are connected by the continuously and convexedly curved end walls 11, which form circular arcs between said opposite ends of the side walls.

Upon the exterior walls of the lunch-pail body and intermediate its upper and lower edges is provided an ornamental band, (designated by the numeral 12.) This band consists of longitudinally-arranged spaced rows of beads 13, between which rows are disposed transversely-arranged lines of slight indentations 14.

Having described the invention, what I claim as new, and desire to secure by Letters Patent, is—

The design for a lunch-pail body, as herein shown and described.

In testimony that I claim the foregoing as my own I have hereto affixed my signature in the presence of two witnesses.

CHARLES E. BERTELS.
